UNITED STATES PATENT OFFICE.

MICHAEL J. McANENY, OF DENVER, COLORADO, ASSIGNOR OF ONE-HALF TO E. N. STROM, OF CHICAGO, ILLINOIS.

AIR-HOSE CONNECTER FOR INFLATING PNEUMATIC TIRES.

Application filed October 23, 1922. Serial No. 596,284.

To all whom it may concern:

Be it known that I, MICHAEL J. McANENY, a citizen of the United States, residing at Denver, in the county of Denver 5 and State of Colorado, have invented a new and useful Improvement in Air-Hose Connecters for Inflating Pneumatic Tires, of which the following is a specification.

My invention relates to an improvement 10 in the commonly used connector-device provided on the end of a hose leading from an air-pressure supply (as at filling-stations) or a pump, for application to the projecting valved tube on a pneumatic tire for inflating 15 the latter; and its is fully explained in the following description and illustrated in the accompanying drawing, in which—

Figure 1 shows my improved device in side elevation, and Figure 2 is an enlarged 20 longitudinal view of the same mainly in vertical section.

A tubular handle-forming connector casing 3 is provided on one end with an internally-threaded socket 3^a to receive the 25 threaded end of a nipple 4, to which is attached a hose 5 leading from a suitable source of air-supply (not shown). The threaded end of the nipple forms with the inner wall of the socket a chamber 6, from 30 the base of which extends a relatively short air-passage 7 terminating in a tubular valve-chamber 8 of a valve-device, the chamber projecting at a right-angle (downwardly) from one side of the casing and having its 35 outer end closed by a screw-plug 9. The valve-chamber 8 communicates through a centrally perforated wall 8^b at its inner end with a tubular extension 8^a, similarly projecting from the casing 3, but from its opposite side and provided with a seat 8^c at 40 its open outer end. The casing terminates at its opposite or forward end in an externally-threaded nozzle 10, on which is screwed a knurled cap 12, which confines 45 against a shoulder 11, formed in the nozzle-end, a gasket 13 of rubber or other suitable material. From the inner end of the valve-chamber extension 8^a there extends lengthwise in the casing an air-passage 7^a, as a continuation of the passage 7 and communicating 50 at its outer end portion with an air-chamber 14 in the nozzle (extending over the gasket 13 therein), through a pair of similar branch air-passages 7^b. The chamber 8 contains a valve 15 seating against the

adjacent face of the wall 8^b and carried on the inner end of a threaded stem 16 which passes through the perforated wall into the valve-chamber extension 8^a, wherein it screws into the inner end of an enlargement 60 16^a of the valve-stem, terminating at its outer end in a button 17 provided on its under side with a facing 18, preferably of rubber.

With my improved connector in operative 65 position, air-pressure from the source of supply, which is confined in the chamber 8, firmly holds the valve 15 normally against its seat to shut off the flow of compressed air. To use the device for its purpose, the 70 nozzle is applied to the ordinary projecting valved tube (not shown) of a tire to be inflated, in a manner to encircle the tube. Thereupon the operator depresses the valve-stem at the button 17, thereby bearing the 75 facing 18 against the seat 8^c to seal the outer end of the chamber 8^a and removing the valve 15 from obstructing the passage 7, which then communicates through the perforation in the wall 8^b with the passages 7^a 80 and 7^b and the air-chamber 14, in which latter it so compresses the gasket 13 about the tire valve-tube as to cause it to closely and tightly hug the tube, when the air-pressure entering the latter through the nozzle 10 opens the tire-valve. This close hugging by the gasket prevents waste of air 85 from the supply by leakage.

After inflation of the tire, the operator releases the button to permit the air-pressure from the source of supply to re-seat the valve 15 and shut off the flow, and the resultant rise of the button off its seat 8^c releases the air-pressure on the gasket 13 from the chamber 14 by way of the passages 90 7^b, 7^a and valve-chamber 8^a about the stem in the latter, thereby permitting the gasket 15 to expand or relax and loosen about the tire-valve tube and enabling the connector to be withdrawn without offering resistance. 95

The advantage of thus releasing the air is that of avoiding having to wrench the connector from the the tire-tube after the inflation, which is ordinarily the case with connectors in common use to the injury of 100 the gasket, causing impairment of the operation of the connector with resultant waste of air-pressure and early destruction of the gasket, requiring the expense of replacement thereof. It even happens sometimes 110

that the gasket hugs so tightly as to prevent withdrawal of the connector in time to prevent bursting of the inflating tire by the excessive pressure introduced therein because of inability to shut it off with the connector operating. All these objections are overcome by my improvement.

I realize that considerable variation is possible in the details of the construction herein shown and described, and I do not intend to limit my invention thereto except as pointed out in the appended claims, in which it is my intention to claim all the novelty inherent in the device as broadly as is permitted by the state of the art.

I claim:

1. A tire-inflating hose-connector having an expansible and contractible gasket in its nozzle, to which leads an air-passage through the connector whereby supply of air under pressure to said nozzle may cause said gasket to expand, and a valve-device interposed in said passage for opening and closing it to the supply of inflating air and including means operating by closure of the valve to vent the introduced air ahead of it away from the gasket.

2. A tire-inflating hose-connector having in its nozzle an expansible and contractible gasket and an air-chamber extending over the gasket, to which chamber leads an air-passage through the connector whereby air admitted to said chamber may cause said gasket to expand, and a valve-device interposed in said passage for opening and closing it to the supply of inflating air and including means operating by closure of the valve to vent the introduced air ahead of it from said chamber.

3. A tire-inflating hose-connector having in its nozzle an expansible and contractible gasket to which leads an air-passage through the connector whereby air under pressure admitted to said passage may cause said gasket to expand, and a valve-device interposed in said passage, normally closing it to the supply of inflating air and provided with means for closing said passage to the atmosphere when the valve is opened and opening said passage to the atmosphere when the valve is closed.

4. A tire-inflating hose-connector having in its nozzle an expansible and contractible gasket and an air-chamber extending over the gasket, to which chamber leads an air passage through the connector, and a valve-device comprising a wall-divided valve-chamber extending transversely through said passage and open at one end, and a valve seating against the dividing wall in one section of the valve-chamber and provided with a stem working through said wall, said stem extending through the other, open-ended valve-chamber section and forming an interposed air-venting passage and carrying on its outer end a button for sealing said open end by depressing the button to unseat the valve for opening said passage to the supply of inflating air whereby pressure admitted to said air chamber may cause expansion of said gasket and venting of the air from said passage may allow the same to contract.

5. A tire-inflating hose-connector having in its nozzle an expansible and contractible gasket and an air-chamber extending over the gasket and to which leads the forward of two relatively-offset sections of an air-passage through the connector, and a valve-device comprising a valve-chamber formed of tubular sections extending from opposite sides of the connector-casing between the adjacent ends of said passage-sections, a dividing wall in one of said chamber-sections at which the rearmost of said passage-sections ends, the forward passage-section, leading from the other chamber-section, having its outer end open to the atmosphere, and a valve having a stem extending through said wall, against which the valve seats, and through said last-named chamber-section to form therewith an interposed air-venting passage, said stem carrying on its outer end a button for closing the open chamber-section end by depressing the button to unseat the valve, whereby pressure admitted to said air chamber may cause expansion of said gasket and venting of the air from said passage may allow the same to contract.

MICHAEL J. McANENY.
